Class 161—194

1 Sheet Drawing. 3 Pages Specification

Preparation of re-enforced synthetic resin articles of manufacture having a decorative wrinkled surface by coating a particular polyester film with a layer of liquid, thermosetting resin containing fibrous re-enforcement material, curing the coated film and stripping away the polyester film. The polyester film is the condensation product of terephthalic acid, isophthalic acid and 1,4-cyclohexanedimethanol in a molar ratio of about 5:1:6.
